X-RAY APPARATUS

Edwin R. Goldfield, University Heights, Ohio,
assignor to Picker X-Ray Corporation Waite
Manufacturing Division, Inc., Cleveland, Ohio,
a corporation of Ohio

Application October 25, 1937, Serial No. 170,810

3 Claims. (Cl. 250—34)

This invention relates to X-ray apparatus and more particularly to an arrangement and form of units thereof by which new technique in fluoroscopy and radiology is facilitated.

5 The invention contemplates a table which may be a tilting table, a pair of X-ray tubes disposed one above and the other below the table, and selective operation of the tubes by a single transformer unit, objects of the invention including 10 such long narrow form and such location of the transformer unit as to permit the shortest connections with the tubes, so that the apparatus occupies less floor area, the upper tube is now rigidly supported and there is least obstruction to 15 the operator of the apparatus.

The exact nature of this invention together with further objects and advantages thereof will be apparent from the following description taken in connection with the accompanying drawing, in which Figs. 1, 2 and 3 are conventionalized 20 views illustrative of an embodiment of the invention observed respectively as in plan, side and end elevations, parts being broken away in Fig. 3 to show units located beneath the table; and Fig. 4 is a diagrammatic view illustrating 25 electrical connections for the parts.

With reference now to the drawing, 1 represents generally a tilting table adjusted horizontally by its usual crank handle 1a to support a patient in prone position. The table is masked at the sides and ends as illustrated and includes within the housing thus formed the usual grid diaphragm assembly 2 and an X-ray tube 3 both having the usual adjustability by the 30 operator through means including handle means 2a at the table side. The table may also be provided with the usual fluoroscopic screen 4.

5 is the upright of a tube stand having a base 6 back of and adjacent the table 1 with runners 40 6a extending alongside the table between the end frame parts illustrated, the tube stand having an arm 7 extending above the table 1 and there carrying an X-ray tube head 8. The tube stand construction permits the usual adjustment of its tube head 8 lengthwise of the base by movement of the upright 5 along the base runners 6a, crosswise of the table by adjustment of the head along the arm 7, and vertically by adjustment of the arm 7 up and down 45 the upright 5. Also as usual the tube head is tiltably adjustable on the arm 7.

A transformer unit 9 of narrow, elongated form, is located closely alongside the table at its back, between the table and the base 6, and between the end frame parts of the latter, the unit

being low enough to be cleared by the arm 7 and screen support column 4a, in any adjusted position.

The housing of the transformer unit, as it appears in Figs. 1, 2 and 3, contains certain electrical apparatus appearing in Fig. 4, of capacity sufficient to serve one of the X-ray tubes 3, 8, a controller unit, preferably mobile, not shown and forming no part of the invention, being provided to permit the operator to adjust the tube 10 operating conditions.

As indicated in Fig. 4, the transformer unit includes a high tension transformer 10, four high tension rectifying valve tubes 11, a filament transformer 12 for each valve tube, and an 15 X-ray tube filament transformer 13, lines L₁ to L₆ leading from the control unit to the transformer unit, lines L₁ and L₂ for control of the transformer 13, lines L₃ and L₄ for control of the 20 transformers 12, and lines L₅ and L₆ for control of the transformer 10.

The described parts within the transformer unit have connections leading to the terminals 14 and 15 within the housing, and the arrangement is such that these terminals supply high 25 tension current, the terminal 14 having two conductors which together supply X-ray tube filament current.

The transformer housing has at its top four terminals, 14a and 14b at one end and 15a and 15b at the other end, thereby providing a pair 30 for each of the terminals 14 and 15 within the housing. The X-ray tube 8 has shockproof cables 8a providing operating connections with the terminals 14a and 15a, and the X-ray tube 3 35 has shockproof cables 3a providing operating connections with the terminals 14b and 15b.

Switch means are provided within the housing of the transformer unit for selectively connecting either X-ray tube with the transformer unit 40 for operation thereby subject to adjustment of a controller 16 on the outside of the unit. Such means is here conventionally shown as a double-pole double-throw switch 14', a single-pole double-throw switch 15', and the linkage 17 interconnecting both switches with the controller 16. In Fig. 4 the controller and switches are shown as adjusted counterclockwise to connect the X-ray tube 8 for operation by the transformer unit, the tube 3 having no operating connection. From this position the controller may be adjusted clockwise approximately 90°, to disconnect the tube 8 and instead connect the tube 3. 45

Conveniently, the table, tube stand, and 50

transformer unit rest upon the floor as indicated in Fig. 3, in close proximity to each other as indicated in Figs. 1 and 3, so that the assembly is decidedly compact, its compactness as a whole being due to considerable extent to the long narrow form of the transformer unit 9. Further, ordinarily the base of the tube stand will be adjacent and alongside a wall of the room in which the apparatus is located; thus in front of the wall Figs. 1 and 2, and to the left of the wall Fig. 3. The usual position of the operator is at the side of the table removed from this wall, from which position the operator may accomplish most of the necessary adjustments of the parts, including all adjustments of the tilting table, the tube 3 and the Bucky tube, tilting and lateral adjustment of the tube 8, most adjustments of the fluoroscopic screen 4, and all adjustments of the control unit if the latter be convenient to the operator at that location as it usually is. For adjustment of the tube stand to move the upper tube 8 vertically or lengthwise of the table, it may be necessary for the operator to step to the far side of the table between the table and the tube stand base. The transformer unit itself, however, is not particularly in the way during such operations, as the upright 5 of the tube stand may be approached either from left or right.

30 For the occasional necessary adjustment of the controller 16 for selection of the X-ray tube to be operated, a remote control may be arranged from the mobile control unit, but in any event the transformer unit is always easily accessible, 35 if manual control only is provided.

This unit, being an expensive and heavy piece of apparatus, and no technique requiring simultaneous operation of both X-ray tubes, its capacity need only be sufficient for operation of 40 one of the tubes. And the necessary and possibly dangerous high tension connections from the transformer unit to the tubes are of the shortest possible length and farthest removed from both operator and patient.

What I claim is:

1. X-ray apparatus of the class described comprising a table having an X-ray tube there beneath, a tube stand having a base adjacent said table and an X-ray tube adjustable above the 5 table, transformer means located closely alongside said table and between said table and said base and substantially midway between the ends of the latter, and means providing shockproof operating connections for selective operation of 10 either of said tubes from said transformer means.

2. X-ray apparatus of the class described comprising a table having a patient-supporting face and an X-ray tube therebehind, said table being mounted for adjustment between horizontal 15 and vertical positions about an axis closer to the foot end than the head end of said face, a tube stand having a base adjacent said table and carrying an X-ray tube for adjustment opposite the table face when the table is in either 20 position, transformer means located between said table and said base to be substantially flush with said table face when the latter is vertically disposed, and means providing shockproof operating 25 connections for both said tubes from said transformer means and including switch means for selectively operating either tube.

3. X-ray apparatus of the class described comprising a table having an X-ray tube there beneath, a tube stand having a base adjacent 30 said table, a column movable along said base, and an X-ray tube carried by said column to be adjustable above the table, said table having a fluoroscopic screen adjustable therealong, with a supporting member extending toward said tube 35 stand base, and movable in a path clearing said tube carrying column, transformer means located closely alongside said table and between said table and said base, and overhung by the path of said screen supporting member, and means providing shockproof operating connections for selective operation of either of said tubes from said transformer means.

EDWIN R. GOLDFIELD.
